DESIGN FOR A WRIST WATCH BAND

Henry R. Wade, Wichita, Kans.

Application March 12, 1934, Serial No. 51,027

Term of patent 3½ years

To all whom it may concern:

Be it known that I, HENRY R. WADE, a citizen of the United State of America, residing at Wichita, in the county of Sedgwick and State of Kansas, have invented a new, original, and ornamental Design for a Wrist Watch Band, of which the following is a specification, reference being had to the accompanying drawing, forming part thereof.

Figure 1 is a plan view of a wrist watch band, showing my new design.

Figure 2 is an edge view of the same.

I claim:

The ornamental design for a wrist watch band substantially as shown.

HENRY R. WADE.
